UNITED STATES PATENT OFFICE.

WILLIAM J. HAMILTON, OF FLINT, MICHIGAN.

RADIATOR.

1,103,010.

Specification of Letters Patent.

Patented July 7, 1914.

Application filed February 13, 1913. Serial No. 748,069.

To all whom it may concern:

Be it known that I, WILLIAM J. HAMILTON, a subject of the King of England, residing at Flint, in the county of Genesee and State of Michigan, have invented certain new and useful Improvements in Radiators, of which the following is a specification, reference being had therein to the accompanying drawings.

10 This invention relates to improvements in radiators especially adapted for use upon motor vehicles for cooling the water which is circulated through the water jacket of the motor for cooling the same.

15 The object of the invention is to provide a simple, cheap and efficient construction of cooling core for such a radiator which will give to the radiator an attractive appearance and be efficient in operation.

20 To these ends the invention consists in the matters hereinafter set forth and more particularly pointed out in the claims reference being had to the accompanying drawings in which—

25 Figure 1 is a front elevation of a device embodying the invention; Fig. 2 is an enlarged vertical section through a portion of the core of the radiator; and Fig. 3 is a horizontal section of the same on the line

30 III—III of Fig. 2.
Radiators embodying this invention may be made in any desired form or size and consist of a top tank A and bottom tank B and a core C between said tanks forming a plurality of water passages 1 connecting the tanks which passages are so shaped as to form between them rectangular air passages 2 extending through the core from front to rear thereof for the free passage of air therethrough, the same passing in contact with the water passages as it passes through the air passages thereby reducing the temperature of the water. Each water passage 1 is formed by two thin sheet metal plates which are spaced a short distance apart to form the water passage between them, by overlapping end flanges 3 which are soldered together to make a tight joint.

45 In overlapping the end flanges 3, should there be an excess of metal at the lateral extension when closing the front and rear edges thereof, the excessive metal can be sheared or buckled without interfering with the general construction of the radiator. To solder the end flanges 3, the same can be dipped in solder whereby the solder will co-

operate with the walls of the flanges in forming a tight joint. The parallel plates 4 and 5 forming each water passage are so bent as to form a tortuous passage having right angle bends, the same forming alternate straight vertical portions 6 connected by straight horizontal portions 7 and the plate 4 forming one side of the passage being bent laterally and folded upon itself opposite one end of each alternate horizontal portion of the passage to form a laterally extending continuation 8 of said horizontal portions, and the plate 5 being bent laterally in an opposite direction from the passage and folded upon itself to form laterally extending continuations 9 of the horizontal portions of the passage which alternate with those having extensions 8 formed by the plate 4.

50 A plurality of the water tubes or passages formed by the plates 4 and 5 as described, are assembled to form the core of the radiator by placing said tubes side by side with their horizontally extending portions in alinement and the lateral extensions 8 of one tube abutting the upper ends of the vertical portions of the next adjacent tube and the laterally extending portions 9 of said adjacent tube alternating with the portions 85 9 and abutting the upper ends of the vertical portions of said first named tube. The assemblage thus forms the rectangular air passages 2 open at their ends through the front and rear faces of the core. Tubes 90 fashioned as described may be accurately and expeditiously made by means of dies which will form each plate of the tube into shape and these plates may then be placed together and their edges soldered to form 95 tubes, and the tubes then assembled in the manner described, and soldered at their meeting points to form the complete core. The upper and lower ends of the tubes are then joined in any suitable manner to the top 100 and bottom tanks of the radiator to permit the water to flow freely through them, the water being retarded in its passage by the right angle bends in the tubes to assist in cooling it and the laterally extending portions of the tube form dead ends where the water will stand until it becomes thoroughly cooled and heavy enough to force its way along the horizontal portions to mingle with the warmer stream and thereby cool the entire body. The angular form of the tubes 110 when assembled gives to the core the appear-

ance of being formed of a plurality of rectangular air tubes extending through the core from front to rear thereof and its appearance is greatly enhanced thereby.

5 Obviously changes may be made in the construction and arrangement of parts without departing from the spirit of my invention and I do not wish to limit myself to the particular form or arrangement shown.

10 Having thus fully described my invention what I claim is:

1. A radiator core comprising a plurality of flat tubes forming vertically extending tortuous water passages, each tube comprising two parallel plates formed with right angle bends to provide straight vertical and horizontal portions, one of said plates being bent laterally and folded upon itself opposite each alternate horizontal portion of the tube to form a lateral extension of said portion corresponding in length to the horizontal portions and the other plate being bent at right angles and folded upon itself to form lateral extensions opposite the ends of the horizontal portions of the tube which alternate with those portions having the lateral extensions formed by the other plate and extending in the opposite direction and corresponding in length thereto; said tubes be-

ing assembled side by side with the laterally extending portions on one tube in abutting engagement with the vertical portions on the next adjacent tube, said horizontally and laterally extending portions of the several tubes being arranged in horizontal aline- 35

ment across the core.

2. A radiator core comprising a series of tubular members forming tortuous water passages, each tube comprising spaced parallel plates formed with right angle bends, 40 straight vertical portions and horizontal portions, each plate having staggered vertical portions connecting horizontal portions, the alternate horizontal portions having lateral extensions provided with return 45 portions forming two-walled ends corresponding in length to the horizontal portions, the two-walled ends of one plate alternating with the two-walled ends of an adjoining plate and thereby providing the two 50 with staggered dead chambers in the same plane as the horizontal portions of the tube.

In testimony whereof I affix my signature in presence of two witnesses.

WILLIAM J. HAMILTON.
